[57] **CLAIM**

The ornamental design for a pivot head flashlight, as shown and described.

DESCRIPTION

FIG. 1 is a perspective view of a pivot head flashlight showing our new design;
 FIG. 2 is a top plan view thereof;
 FIG. 3 is a bottom plan view thereof;
 FIG. 4 is a left side elevational view thereof;
 FIG. 5 is a right side elevational view thereof;
 FIG. 6 is a front elevational view thereof;
 FIG. 7 is a rear elevational view thereof; and,
 FIG. 8 is a left side view of a second embodiment in which the head is pivoted 90°.
